UNITED STATES PATENT OFFICE.

WILLIAM E. RIVERS, OF OLDBRIDGE, NEW JERSEY, ASSIGNOR TO THE
OLD BRIDGE ENAMELED BRICK AND TILE CO., OF NEW JERSEY.

KILN FOR CERAMIC WARES.

SPECIFICATION forming part of Letters Patent No. 693,155, dated February 11, 1902.

Application filed June 9, 1898. Serial No. 682,994. (No model.)

To all whom it may concern:

Be it known that I, WILLIAM E. RIVERS, a subject of the Queen of Great Britain, and a resident of Oldbridge, in the county of Middlesex, in the State of New Jersey, have invented certain Improvements in Kilns for Ceramic Wares, of which the following is a specification.

My invention relates to the class of down-draft-kilns employed in burning pottery, tiles, and similar ceramic wares; and the objects of the invention are to effect an economy in the construction of the kiln, an economy in the fuel consumed, an economy in the matter of injured wares, owing to facilities for getting rid of the sulfur fumes and the better distribution of the heat in the kiln, and better facilities for cleaning out the flues than is usually attained in kilns of this class.

20 In the drawings which serve to illustrate my invention, Figure 1 is a vertical diametrical section in the plane indicated by line x' in Fig. 3. Fig. 2 is a similar section to Fig. 1 in the plane indicated by line x^2 in Fig. 3. Fig. 3 is a horizontal section in the plane indicated by line x^3 in Fig. 2, but on a smaller scale. Fig. 4 is a horizontal section in the plane indicated by the broken line x^4 in Fig. 1, but also on a smaller scale.

25 A is the oven of the kiln, wherein the ware to be burned is placed, and B is the floor of the same. In the walls at the base of the kiln is a series of furnaces C, equally spaced, as usual, the number of same being governed by the diameter of the kiln. As herein shown there are eight. The furnace C has some special features for effecting an economy in fuel. The grate or fire-bed c is inclined, and the roof or crown c' is also inclined or pitched inward to a somewhat greater degree than the fire-bed, so that the furnace is considerably deeper vertically at the door or entrance c^2 than at the inner end, where it opens into the flue c^3 , leading up into the oven or chamber

30 A close to the outer wall. At the inner end of the fire-bed there is an inclined wall c ^{4} , leading up to the flue c^3 and usually formed in steps, as shown. This form of furnace produces very perfect combustion and reduces 35 the amount of fuel ordinarily consumed to a very material extent. There may be also a

small flue c^5 leading from the furnace back under the floor B to a central flue or aperture c^6 in the floor common to all the furnaces C.

55 In the crown D of the oven A are outlets d, one above each of the flues c^3 , these outlets being controlled by dampers d', operated by suitable means—as levers and chains, for example. In the center of the crown and directly over the aperture c^6 in the floor is an outlet d ^{x} , controlled by a damper d ^{x} . The object of these outlets in the crown D is to permit the escape of smoke and fumes from the oven until the fires are well under way and the sulfur and free carbon driven off, after which they will be closed by their respective dampers or covers and the draft be compelled to pass down into the flues below the floor and thence to the chimney-flues.

60 The construction below the floor B will now be described with especial reference to Figs. 1, 2, and 3.

65 Below the floor is a large annular flue E, concentrically arranged, from which radial flues F lead to upright chimney-flues G. Preferably there will be four of these flues, equally spaced. Within the annular flue E is a lesser annular flue H, the two flues E and H being connected by short radial flues I, equal in number to the flues F, but alternating with them in position, so that the wall J, separating the flues E and H, will be opposite to the inner ends of the radial flues F. This arrangement permits of access to the flues for sweeping them and also provides for a substantially 80 equal distribution of the currents of heated gases throughout the kiln. The downdraft from the oven A to the flues below is by way of passages a, suitably formed in the floor B. These may be situated as desired, but they 85 will be by preference distributed in a substantially uniform manner over the floor. They may be all left open or some of them covered temporarily at certain points, as dictated by the judgment of the operator.

90 The flues c^3 and c^6 , which lead the furnace-gases up into the chamber or oven A, may be built up and lengthened into chimneys temporarily by loose tiles or bricks, so as to open at a higher point in the oven, if desired. This 95 will be governed by the judgment of the operator.

By the employment in a kiln of the construction shown the kiln may be heated with much less fuel than when constructed in the usual way and the injurious effect of sulfur from the fuel on the wares being burned is also avoided.

I am well aware that, broadly speaking, it is not new to provide a downdraft-kiln with annular concentrically-arranged flues below the floor of the kiln, and I do not broadly claim them.

Having thus described my invention, I claim—

1. The combination with a kiln for burning ceramic wares, of a furnace therefor having its crown inclined downward toward its inner end, a grate also inclined downward toward its inner end but at a less angle than the crown, whereby the gas-outlet is contracted, an ash-box under said grate, a main gas-outlet inclined upward, and an upright flue c^3 and a horizontal flue c^5 , branching from the

upper end of said gas-outlet, substantially as set forth.

2. A circular kiln for burning ceramic wares, having a series of furnaces about the same with gas-flues c^5 c^6 leading therefrom into the oven A, a large annular flue E, below the flues c^5 , with radial flues F leading therefrom to as many chimney-flues, a lesser annular flue H, within the space circumscribed by the flue E, radial flues I, connecting the flues E and H, and flues or passages a , for downdraft, extending through the floor from the oven A to the flues E and H, substantially as set forth.

In witness whereof I have hereunto signed my name, this 7th day of June, 1898, in the presence of two subscribing witnesses.

WILLIAM E. RIVERS.
